UNITED STATES PATENT OFFICE

CECIL H. LAWRENCE, OF ATTLEBORO, MASSACHUSETTS, ASSIGNOR TO EVANS CASE COMPANY, A CORPORATION OF MASSACHUSETTS

DESIGN FOR A TABLE LIGHTER

Application filed September 17, 1930. Serial No. 37,004. Term of patent 7 years.

To all whom it may concern:

Be it known that I, CECIL H. LAWRENCE, a citizen of the United States, residing in Attleboro, county of Bristol, State of Massachusetts, have invented a new, original, and ornamental Design for Table Lighters, of which the following is a specification, reference being had to the accompanying drawing, forming part thereof.

In the accompanying drawing,

I claim:

The ornamental design for a table lighter substantially as shown and described.

CECIL H. LAWRENCE.
